UNITED STATES PATENT OFFICE.

JOSEPH SZABO AND STEVEN SZABO, OF LOS ANGELES, CALIFORNIA.

BED DAVENPORT.

Application filed June 29, 1925. Serial No. 40,333.

The object of this invention is to make certain improvements in detail and construction, and especially in the mechanism used in converting the bed davenport from a position when used as a seat into that for use as a bed and vice versa, of the davenport described and claimed under our co-pending application Serial No. 715,817, filed May 26, 1924.

10 To this end our invention consists in similar construction and combination of parts, as thereinbefore described and claimed, with the following improvements added hereunto.

15 In the accompanying drawing forming a part of this specification:

Figure 1 is a transverse sectional elevation taken on line 3—3 of Figure 3 showing the spring and link arrangement of the 20 bed davenport in a closed position when used as a couch or seat.

Figure 2 is a transverse sectional elevation taken on line 3—3 of Figure 3 showing the spring and link arrangement and illustrating the position of the bed davenport in 25 open form when used as a bed.

Figure 3 is a plan view, showing the bed davenport in an open position.

Figures 4 and 5 represent a side elevation of the link mechanism in closed and open position respectively, of the bed davenport in couch and bed form.

Figure 6 is a side elevation showing the first step in opening the davenport, in 35 which the back is folded down on the seat.

In the drawing the same reference characters are used to denote similar parts as described in our co-pending application, hereinbefore referred to, the natural sequence of order following for the new parts 40 herein described.

The stationary structure (1) comprises a base frame member (2), a back frame member (4), upholstered seat (5), end arms (6) and legs (3) upon which said base frame is mounted.

50 Loose seat cushions (7) are placed on the seat (5) when the bed davenport is used as a couch. An upholstered back (8) includes a frame (9) to the corners of which frame are screwed metal flanges (47) and (40) respectively, each of said flanges having pivotal connections (39) and (46) with operating links and bars; the upper flange (47), as in Figures 1 and 4, being pivotally connected through the medium of an ad-

justable supporting leg (45) by pins (46) and (44) to the operating link (43), the lower flange (40) pivotally connecting the operating bar (34) by a pin (39) and also 60 fastened with the lever (43) by a pin (42) at the branch terminal (41) of the operating bar (34).

The lower end of operating bar (34) is made in the form of a T head, into which 65 is centrally apertured a square slot (43) and in the extremities of said T are holes (35) which are adaptable to engage the springs (36) whose actions are equal and opposite in direction, the forward end of 70 one spring being connected at (16) to the inside of the front rail member (2) and the rear end of the opposite acting spring being connected at (38) to the inside of the rear of the same base frame member, by 75 a connecting link (37).

Transversely connecting the operating mechanism is a shaft (49) which is journaled on the cross bar of the frame, having square ends, which are wedged into the 80 square slot in the T head portion of operating bar (34) and holds the upholstered back (8) in balance, while the operating bar (34) is rotated on shaft (49) as a pivot when the bed davenport is converted from 85 a couch to a bed position.

An upholstered strip (29) projects forward from the upper edge of the back frame (4) and extends over the rear upper edge of the back (8) when folded, thus giving the upper rear edge of the bed davenport a neat finish.

When the back (8) is folded as shown in Figure 1, the operating levers (43) and adjustable legs (45) are folded and concealed 95 along the end edges of the back frame (9).

The operation of converting the bed davenport from a couch position as shown in Figure 1 to that of a bed position as shown in Figures 2 and 3 consists of grasping the upper portion of the back (8) and gently tipping it forward from a slightly inclined position to a vertical position and folding the same over until it rests upon seat (5), as shown in Fig. 6, it being guided 100 in this movement by the levers (43), revolvable about pins (42) as an axis. This brings the web band (50) into view. The fingers are then placed beneath the web band (50) and a gentle pull is exerted thereon, causing 105 the operating bars (34) rigid with the transverse shaft (49) to be swung for- 110

wardly, this movement being assisted by the springs (36) exerting a pull due to the tension therein until the operating bar (34) comes in a vertical or neutral position. As the back (8) is folded in a further direction until its face comes flush with the seat (5) it does so practically due to its own weight, storing tension at the same time in the tension springs to be used again in converting the bed to a couch position.

During the final rotation of the back (8) from its neutral or vertical position to that of being flush with the seat (5) in the down position, the links (43), by means of pins (44), automatically force the adjustable legs (45) about the pins (46) as an axis from their folded position to that of an open position.

Throughout this movement of the rotation of the back (8) from an open position in bed form until closed position in a couch form, the same method of operation is necessary and the springs function in like manner, so that the conversion of the bed davenport from one use to another is practically automatic, due to the equal action and reaction of the tension in the springs.

When the back is folded, the loose cushions (7) are placed on the seat (5) to be sat upon, thus making it unnecessary to upholster the face (30) of the seat, which is used for sleeping purposes upon the removal of the cushions and unfolding the back (8).

The outside face (31) of the back (8) is upholstered, so that one may recline against the same while sitting on the davenport when folded as a couch. The inside or rear face (32) of the back is not upholstered and is used for sleeping when the back is let down to convert the bed davenport into a bed.

The upholstery of the seat (5) and back (8) may be provided with the best mattress springs.

It will be noted that there are few operating parts entering into the mechanical construction of this bed davenport, those parts being simple and not liable to get out of order. They operate easily and efficiently and are cheap to manufacture.

The easy and automatic adjustability of all the parts in general, requiring little effort in the conversion from one position to another, the simplicity of all co-functioning parts, are exhibiting factors which make this device an article worth while.

Having thus described our invention, we claim:

1. A bed davenport comprising in combination a base frame member, including crossbars connected to a back frame member, a movable upholstered back included in said back frame member, upholstered seat, and arms and legs upon which said base frame is mounted, a longitudinal shaft journaled on

the cross bars and near the transverse centers of said base frame member, T shaped operating bars carried by the ends of said shaft and adapted to be swung forwardly and rearwardly thereon, upper and lower metal flanges secured to the corners of aforesaid movable upholstered back, the said lower metal flanges being pivotally connected to the remote ends of said operating bars, a pair of adjustable supporting legs pivotally connected to said upper flanges; a pair of operating links, each pivoted at their opposite ends to said adjustable supporting legs and T shaped operating bars, respectively, at points adjacent to the pivotal points of the latter with said flanges, whereby to permit the said movable upholstered back to be swung over the stationary upholstered seat, when the bed is swung from opened to closed position and vice versa, normally tensioned retractile springs having their inner ends connected to the T heads of said operating bars at points on opposite sides of and equidistant from the points of connection between the bars and shaft, the outer ends of the springs being connected respectively to the front and rear portions of the ends of the base frame, the said springs assisting in producing a torque whereby to aid in the manual operation of swinging the movable upholstered back from couch to bed position and vice versa aforementioned.

2. In a bed davenport, the combination of a stationary frame structure comprising a base frame member, a back frame member, an upholstered seat, end arms, and legs upon which said base frame is mounted; an upholstered foldable back included in said back frame member, metal flanges secured to the outside upper and lower corners thereof, pivoted means for securing said metal flanges through the medium of adjustable supporting legs and T-shaped operating bars to a supporting means carried by the base frame whereby said back may be rotated into a superimposed position over said upholstered seat and then swung forwardly in front of and flush with said upholstered seat; means to promote the initial movement and sustain the final movement of the manual operation of aforesaid movement of converting the bed davenport from a couch to a bed position and vice versa and means whereby, during the last movement first mentioned aforesaid adjustable legs are unfolded, thereby supporting said foldable back in said bed position.

3. A bed davenport, comprising a stationary structure consisting of a base frame and a back frame, including a seat in said base frame, a movable back in said back frame, metal flanges secured to the upper and lower corners thereof, movable legs pinned to said upper flanges, swinging T-shaped operating bars pinned to said lower

flanges, operating links pivotally connecting said movable legs and said operating bars, a horizontal bar journaled in aforesaid base frame and rigidly connected to aforesaid 5 operating bars, normally tensioned retractile springs having their inner ends connected to the T heads of said operating bars at points on opposite sides of and equidistant from the points of connection between 10 the operating bars and horizontal bar, whereby to produce a force in moving said operating bars in the same direction, thereby assisting in the initial and retarding in the final movement, during the conversion 15 of the davenport from a couch to a bed position and vice versa.

4. In a bed davenport, the combination with a base frame and a back member of a shaft journaled in the base frame, arms carried by the ends of said shaft, said arms having T-heads, normally tensioned, retractile springs having their inner ends connected to the T-heads of said arms at points on opposite sides of and equidistant from the 20 points of connection between the arms and shaft, the outer ends of the springs being connected respectively to the front and rear portions of the ends of the base frame; plates on the lower portions of the ends of the back member, to which plates the ends of the arms are pivotally connected, leg members pivotally connected to the upper portions of the ends of the back member and links having their upper ends pivotally connected to said leg members at 25 points adjacent to the pivotal points of the latter and the lower ends of said links being pivotally connected to the arms at points adjacent to the points of pivotal connection 30 of the latter with said plates.

5. A bed davenport, comprising in combination a base frame member, including cross bars connected to a back frame member,

an upholstered back included in said back frame member, upholstered end arms and 45 legs upon which said base frame is mounted, a longitudinal bar journaled on the cross bars and near the transverse centers of said base frame member, T-shaped operating bars uprightly fastened to the outer ends 50 thereof, which are adapted to rock when said upholstered back is folded over and converted from a couch to a bed position and vice versa; means to initiate said rock, consisting of normally tensioned retractile 55 springs having their inner ends connected to the T-heads of said operating bars at points on opposite sides of and equidistant from the points of connection between the operating bars and shaft, the outer ends of 60 the springs being connected respectively to the front and rear portions of the ends of the base frame, plates on the lower portions of the ends of the back member, to which plates the ends of the operating bars are 65 pivotally connected, foldable leg members pivotally connected to plates on the upper portions of the ends of the back member and links having their upper ends pivotally connected to said foldable leg members at 70 points adjacent to the pivotal points of the latter and the lower ends of said links being pivotally connected to the operating bars at points adjacent to the points of pivotal connection of the latter with said plates, 75 the pivotal connections of the link to the operating bar and foldable leg member being equi-distant from the pivot joints which hinge aforesaid operating bar and foldable leg member to the lower and upper 80 plates of the back member respectively.

In testimony whereof we have hereunto subscribed our names this 22nd day of June,
A. D. 1925.

JOSEPH SZABO.
